J. BRUCE

REVERSE LEVER CONNECTING AND LOCKING MEANS

Filed April 15, 1926

UNITED STATES PATENT OFFICE.

JAMES BRUCE, OF OKLAHOMA CITY, OKLAHOMA.

REVERSE-LEVER CONNECTING AND LOCKING MEANS.

Application filed April 15, 1926. Serial No. 102,227.

This invention relates to the reverse levers and reach rods of locomotives, and more particularly to the means by which these parts are connected and the reverse levers held against casual movement.

The invention has for one of its objects to improve and simplify the general construction of means of this character, and to attain these ends comprehends the employment of an eccentric to connect the reverse lever and reach rod and a notched member carried by the connection for engagement by the latch which holds the reverse lever against casual movement.

The invention is hereinafter fully described and claimed, and illustrated in the accompanying drawing, wherein:

Figure 1 is a view in side elevation of a reverse lever and reach rod connected by means constructed in accordance with my invention.

Figure 2 is a sectional view taken on the plane indicated by the line 2—2 of Figure 1, and

Figure 3 is a similar view taken on the plane indicated by the line 3—3 of Figure 2.

Corresponding and like parts are referred to in the following description, and designated in the several views of the accompanying drawing, by similar reference characters.

In the drawing, 1 designates the reverse lever and 2 the reach rod of a locomotive. These parts are connected by an eccentric 3 and strap 4. The eccentric 3 is adapted to be pivotally supported by a bolt 5, and the lower forked end 1^a of the reverse lever 1 is secured to the eccentric by this bolt and a bolt 6. The eccentric 3 is provided with a peripheral groove 7 for the reception of the strap 4 which is secured to and within the forked end 2^a of the reach rod 2 by a bolt 8.

The forked end 1^a of the reverse lever 1 embraces the eccentric 3 and the upper portion of the eccentric strap 4. A notched strap or quadrant 9 is secured to the upper side of the eccentric strap 4 by bolts 10. This part and a latch bolt 11 carried by the reverse lever 1, are adapted to secure the reverse lever against casual movement. The latch bolt 11 is yieldingly retained in engagement with the notched quadrant 9 by means of a spring 12, and is adapted to be

retracted or withdrawn from engagement with the notched quadrant by a thumb lever 13 pivoted as at 14 to the reverse lever 1 and connected to the latch bolt by a link 15.

From the foregoing description and accompanying drawing, it will be apparent that the means for connecting the reverse lever 1 to the reach rod 2 and the means for holding the reverse lever and reach rod against casual movement are compactly arranged, that on withdrawing the latch bolt 11 a positive rearward or forward thrust may be imparted to the reach rod 2 through the medium of the reverse lever 1, and that upon releasing the latch bolt these parts will be positively locked against casual movement. It should be understood that the drawing is merely illustrative and does not pretend to give exact proportions. Furthermore, the said drawing is illustrative of a preferred construction, it being my expectation that various changes and modifications may be made without departing from the spirit and scope of my invention. The device may be, as should be apparent, used as a steering device for tractors and other vehicles and in connection with the main throttles of locomotives.

What is claimed is:

1. In combination, an eccentric, a strap therefor, a lever connected to the eccentric, and means associated with the lever and strap for securing all the parts against relative movement.

2. In combination, an eccentric, a strap therefor, a lever connected to the eccentric, a notched member carried by the strap, and a latch carried by the lever for cooperation with the notched member.

3. In combination, a pivoted eccentric, a strap therefor, a reverse lever secured to the eccentric, a reach rod secured to the strap, a notched member carried by the strap, and a latch carried by the reverse lever for cooperation with the notched member.

4. In combination, a pivoted eccentric, a strap therefor and provided with a notched part, a reverse lever pivoted to the eccentric, a reach rod connected to the strap, a latch carried by the reverse lever for cooperation with the notched part of the strap.

In testimony whereof I affix my signature.
JAMES BRUCE.
